UNITED STATES PATENT OFFICE.

EDWIN E. BARNEY, OF NEW ROCHELLE, NEW YORK, ASSIGNOR TO REMINGTON TYPE-WRITER COMPANY, OF ILION, NEW YORK, A CORPORATION OF NEW YORK.

TYPEWRITING MACHINE.

Application filed June 18, 1926. Serial No. 116,845.

My invention relates to typewriting machines and more particularly to paper feed mechanism therefor.

The main objects of my invention, generally stated, are to provide, simple, light and compact paper feed devices, that are inexpensive to manufacture and may be readily assembled in the machine and detached therefrom when desired. The mechanism 10 of my invention is designed more especially for light, portable typewriting machines in which the provision of devices having the above mentioned characteristics constitute such an important factor, although such devices are available for embodiment in other types of typewriting and like machines.

To the above and other ends which will hereinafter appear, my invention consists in the features of construction, arrangements of parts and combinations of devices set forth in the following specification and particularly pointed out in the accompanying claims.

In the drawings wherein like reference 25 characters designate corresponding parts in the various views,

Fig. 1 is an enlarged, detail, fragmentary, vertical, fore and aft, sectional view of a carriage equipped with the devices of my invention; the section being taken on the line 1-1 of Fig. 4 and looking in the direction of the arrows at said line.

Fig. 2 is a like view of the same, taken on the line 2-2 of Fig. 5 and looking in the direction of the arrows at said line, the parts being shown in the released position.

Fig. 3 is a detail, bottom plan view of the combined paper table and apron, shown detached.

Fig. 4 is a detail, top plan view of the carriage, with the platen and combined paper table and apron broken away.

Fig. 5 is a vertical, transverse sectional view of the carriage with the platen removed, the section being taken on the line 5-5 of Fig. 4 and looking in the direction of the arrows at said line.

Fig. 6 is an enlarged, detail, fragmentary, top plan view, with the parts sectioned away, of the releasing shaft, its holding latch and some of the other associated parts; the view showing the latch released from the shaft to permit its removal.

Fig. 7 is an enlarged detail, side view of

one of the supporting brackets, showing 55 in cross section the rock shaft supported thereby.

Fig. 8 is an enlarged, detail, fragmentary perspective view of one of the feed roller hangers.

I have shown my invention embodied, in the present instance, in a Remington portable machine, only so much of said machine being shown as is necessary to illustrate my invention in its embodiment therein. The devices of the present invention are such that they may be readily incorporated in said machine without modifying, or materially modifying, other structural features of the machine as they now exist.

It is a feature of the present invention that when the platen is removed from the carriage in the usual manner, the shifting of a latch permits the independent removal of the combined paper table and apron, together with the platen and carriage-scales mounted thereon. This leaves exposed, and gives access to, the independently mounted forward and back feed rollers, and feed roller releasing means, located below the paper apron, and if desired, a removal of the carriage releasing means may then be readily and independently effected. This not only provides means that enable the parts to be rapidly assembled in the machine, but enables access to be readily had to parts that ordinarily are more or less inaccessible for ready adjustment, replacement or repair.

The carriage of the Remington portable machine comprises a base plate 1 mounted on crossed supporting rollers 2 in the usual manner, to guide the carriage on its case shifting support 3 to travel from side to side of the machine. The forward supporting rollers are not shown.

The platen 4 is mounted on the usual detachable spindle 5 that enables the platen to be readily removed when desired; said spindle being supported by end plates 6 fixed to the base plate 1 of the carriage.

A combined paper table and apron 7 inclines upwardly and rearwardly in the rear of the platen and is curved beneath the latter to form a paper apron which terminates at its front edge 8 in front of the platen. This member 7 is provided with depending ears 9 perforated to provide bearing open-

ings for pivots 10 and 11. The member 7 as a whole is thus pivotally supported on the carriage to swing from the position shown in Fig. 1, to that indicated in Fig. 2, and vice versa. Normally, the front edge 8 of the member 7 is lightly pressed against the platen on a work sheet thereon, as shown in Fig. 1, by a leaf spring 12, secured at its lower end to the base plate 1 by a screw 13.

10 The upper free end of this spring bears with a rearward pressure against the front of the member 7, thus tending to hold it in the Fig. 1 position.

The member 7 is provided with openings 14 for the rear paper feed rollers 15, and is recessed at 16 in its front edge to receive the front paper feed rollers 17. An angular scale plate 18, which extends throughout the length of the member 7, is 20 provided with depending ears 19, bifurcated at their lower ends, at 20, to straddle headed screws 21. The stem of each screw 21 passes freely through the slot in the associated bifurcated ear 19, and through a horizontal 25 slot 22 in the upright portion of a forwardly and upwardly extending bracket arm 23, formed on an end of the member 7. The rear threaded end of each screw is received in a nut 24 (see Fig. 5) back of the companion bracket arm 23, each nut being preferably shaped as shown to prevent it from turning. This connection between the member 7 and the scale plate 18 enables the latter to be adjusted longitudinally, and also 30 up and down on the member 7 to obtain a proper adjustment of the scale plate at each end thereof. By tightening the screws 21 the parts will be clamped together between the head of each screw and its companion nut 24.

From an inspection of Fig. 4 it will be seen that there are scale markings at both the upper and lower edges of the scale plate 18, one set of markings constituting a platen 45 scale and the other set a carriage scale.

The pivot pin 11 for the combined paper shelf and apron projects inwardly from the upright arm of a bracket 25 fixed at 26 to the base plate 1 of the carriage. The other 50 pivot 10 projects inwardly from the upright arm of a bracket 27. This last mentioned bracket in the present instance constitutes part of a latch or holding device 28, as will hereinafter more clearly appear. Referring more particularly to Fig. 6, it will be seen that the foot piece 29 of this bracket rests on the upper surface of the base plate 1 of the carriage and is shiftably mounted thereon from the Fig. 4 connecting position to, say, the Fig. 6 releasing position. The manner of mounting member 27 in the present instance, is to tap the foot piece 29 for the reception of two headed screws 30 and 31. The stems of these screws 60 pass up through a slot 32 in the base plate

1 of the carriage into the tapped openings in the foot of the member 27. The slot 32 extends longitudinally in the direction of the travel of the carriage and is of sufficient length to permit the member 27 to be shifted in a straight line to the left from the Fig. 4 position, where the pivot 10 is seated in its bearing in the companion ear 9, to a releasing position where the pivot 10 is withdrawn from its bearing opening. 70 When the member 27 is in the last named position the combined paper table and apron may be released from its pivot 11 and detached from the machine, assuming the platen has first been removed. When the member 7 is mounted in place, as indicated in Fig. 4, a tightening of the screws 30 and 31 will clamp the member 27 to the carriage and hold it against accidental displacement. 80

The slot 32 in the base plate has a lateral extension 32^a in which the stem of the screw 31 may swing, as shown in Fig. 6, to enable the member 27 to receive a pivotal movement around the screw 30 and assume an angular position after the pivot 10 has been withdrawn from its bearing opening in the associated ear 9 of the paper table. The effect of this is to shift the part or locking latch 28 from its holding position, shown in Fig. 4, to its releasing position, shown in Fig. 6 for purposes which will presently appear. 90

The rear main paper feed rollers 15 are loosely mounted on a supporting rod or spindle 33, and are maintained separated thereon by spacing sleeves 33^a. The ends of the spindle 33 are loosely supported in barrel-like bearings 34 in sheet metal hangers 35 and 35^a, the ends of the spindle being slightly headed to prevent longitudinal displacement of the spindle in its bearings. Each hanger 35 and 35^a is shaped somewhat like that shown in detail in Fig. 8 and extends fore and aft of the machine 100 and is provided at its lower end with bent-down, integral, parallel ears 36. These ears are perforated to form bearing openings that receive a pivot rod 37. Secured by screws 38 to the upper side of the base plate 1 of the carriage, near the right hand end thereof, is a sheet metal bracket 39. One side of this bracket has a barrel-like seat 40 to receive and hold therein one end of the companion pivot rod 37. At the other side of the bracket is an upstanding arm 41 perforated to form a seat for the other end of the said last mentioned pivot rod, and thus pivotally support the hanger 35 on the base plate 1 of the carriage. The hanger 35^a which supports the other end of the feed roller spindle 33 is constructed and mounted in a like manner and corresponding reference numerals will be applied to the parts where they are alike. 110

Corresponding forwardly extending hangers 42 and 43 for the spindle 44 of the forward feed rollers 17 are constructed and mounted on the pivot rods 37 in the same manner as the hangers 35 and 35^a, previously described. Thus, each of the hangers 42 and 43 has integral, parallel ears 45 mounted on the companion pivot rod 37, and has a bearing 46 at its forward end to support the spindle 44, whereas the feed rollers 17 are maintained spaced apart on their spindle 44 by spacing sleeves 47. A single spring 48 is provided for each companion pair of hangers 35 and 42, 35^a and 43. Each of these springs is coiled around its companion pivot 37, and bears at one end 49 against the forward hanger and at its opposite end 50 against the rear hanger, tending to force the free ends of both hangers towards the platen. It will be seen that the hangers of each companion pair 35, 42 and 35^a, 43 are arranged one in front of the other and in fore and aft alignment, although the spindle supporting arms of the forward hangers are off-set outwardly from the spindle supporting arms of the rear hangers. It will be seen, moreover, from an inspection of Figs. 2 and 8 that each hanger is angular in cross section and that the hangers of each companion pair 35, 42 and 35^a, 43 are spaced apart above their pivot 37, and intermediate said pivot and the platen. By this arrangement a releasing device, in the nature of a rock shaft 51, may be readily positioned intermediate the hangers of each pair, to coat with the flat face of the sheet metal body portion of each hanger, and when desired may be readily removed upwardly from such position and detached from the machine, as will now be explained.

The rock shaft 51 is preferably angular in cross-section, not only where it coats with the feed roller hangers to cam them to releasing position, as shown in Fig. 2, but substantially throughout the length thereof to give added rigidity to the shaft. One end of the shaft is formed with a reduced cylindrical portion 52 where it is received in a circular bearing opening in a bracket arm 41^a, which corresponds to the bracket arm 41, except as will hereinafter appear. Near the opposite end of the rock shaft 51 is a reduced cylindrical bearing portion 53 which, as shown in Fig. 7, is seated in an open-mouth bearing 54 in the bracket arm 41. It will be seen therefore that the bracket arms 41 and 41^a differ in that the arm 41 has a circular bearing opening for one end of the shaft 51, whereas the arm 41^a has an open-mouth bearing 54 from which the shaft 51 may be withdrawn. When the shaft 51 is seated in its bearings as indicated, the squared inner portion of the shaft adjacent to the part 53 thereof will bear against the inner face of the bracket arm 41. This pre-

vents the shaft from shifting longitudinally to the right, or to the left as the parts appear in Fig. 6, and prevents the shaft from being unseated from its bearing in the bracket arm 41^a. On the other hand, the shoulder, formed where the cylindrical reduced end 52 joins the squared portion of the shaft, is adapted to coat with the inner face of the bracket arm 41^a and limit the longitudinal motion of the shaft to the left, or to the right as the parts appear in Fig. 5.

The shaft 51 is extended to the right, or to the left as shown in Fig. 4, and projects through a slot 55 (Fig. 2) in the right-hand end plate 6 of the carriage. An arm 56 is secured to the outer end of the shaft 51 and terminates in a finger piece 57 by which the shaft may be rocked from the Fig. 1 to the Fig. 2 position. In this last named position the arm 56 coats with a stop pin 58 secured to and projecting outward from the right-hand end plate 6 of the carriage.

In order to prevent the shaft 51 from being accidentally unseated from its bearings I employ a suitable releasable latch, holding or retaining device, in the present instance represented by the part 28, hereinbefore described, of the member 27. When the parts are in the normal, holding position, represented in Fig. 4, the latch 28 overlies the part 53 of the shaft and prevents a movement of said part up in the open-mouth bearing 54 in the bracket arm 41. As long as the latch 28 is retained in this position, the shaft 51 cannot be removed. When, however, the latch 28 is moved to one side, as shown in Fig. 6, the shaft may be lifted up in its bearing 54 until the squared portion clears the bracket arm 41. Then the shaft may be shifted to the right and the reduced end 52 thereof unseated from its bearing, and the shaft removed from the machine; the slot 55 in the right-hand end plate facilitating such removal. The removal of the shaft 51 in the manner just described, of course, assumes that the platen and combined paper table and apron have first been removed from the machine.

When the feed rollers are released by rocking the shaft 51, it is desirable, by the same operation, to release the forward edge 8 of the paper apron from the platen or the work sheet thereon. In order to effect this result I have provided two forwardly and downwardly projecting extensions 59 on the forward edge of the paper apron 7. The horizontally disposed arm of each extension 59 extends over the spindle 44 and the downwardly extending vertically disposed arm is arranged in front of the spindle, or a spacing sleeve 47 thereon. Preferably, there is a lost motion between each cooperating spacing sleeve 47 and the extension with which it coats in the movement of the feed rollers 17 from the Fig. 1 to the Fig. 2 position.

The result is that at the last portion of the releasing movement of the forward feed rollers, the extensions 59 will be contactively engaged, and the combined paper table and apron turned on its pivots from the Fig. 1 to the Fig. 2, released position. When the feed rollers are returned to normal position the spring 12 turns the combined paper table and apron 7 on its pivots back to the normal, 10 Fig. 1, position.

It may be here pointed out that the provision of the extension 59 does not interfere with the ready removal of the combined paper table and apron 7 in the manner hereinbefore described, since a mere lifting of the member 7 frees it from the forward feed roller spindle 44.

From an inspection of Fig. 1 it will be seen that the releasing shaft 51 does not normally receive the pressure of the spring-pressed feed roller hangers 35, 42, 35^a, and 43, so that the full pressure of the springs 48 is exerted through the feed rollers 15 and 17 against the platen, or the work sheet thereon. 20 When, however, the shaft 51 is turned from the Fig. 1 to the Fig. 2 position, the front and rear sets of hangers will be cammed away from each other until the shaft is arrested by the arm 56 coacting with the stop 25 58. At this time opposite diagonal corners of the shaft coat with the hangers, the pressure of the latter on being exerted in opposite directions towards the axis of the shaft effecting substantially a dead center thrust 30 thereon. In practice I prefer to arrest the shaft slightly over the exact dead centering position, as shown in Fig. 2, to effect a more reliable holding of the parts. This holds the shaft in the position to which it has been 35 turned by the limit of its releasing movement; locking or holding the paper feed devices released until the finger piece 57 is moved forward to break the dead centering arrangement of the parts. A movement of 40 45 the finger piece 57 back to a point short of where the parts are substantially dead centered is sufficient to release the paper feed devices without, however, locking them in the released position. When the operator 50 releases the finger piece 57 after such an operation the parts will be returned to normal positions by the springs 48 and 12.

It will be understood that by the present arrangement the forward and rear feed roller hangers exert a balanced spring pressure against the interposed rock shaft 51 during the releasing movement of the parts, and that such pressure is exerted on diametrically opposite sides of the shaft. It follows 55 60 therefore that a comparatively light shaft and bearings therefor may be employed, which is an important factor where the parts must necessarily be in such a compact arrangement as provided in the present instance, and where lightness and compactness

of the parts, as well as low cost of manufacture, are such important factors in the production of a portable machine.

It also will be understood that the construction of the present invention enables the parts to be quickly assembled in manufacture, as well as giving ready access to and removal of parts for the purpose of repair or replacement, when required. Also that the features of the invention may be readily included in the Remington portable machine without modifying, or materially modifying, other structural features thereof.

Various changes may be made without departing from my invention as it is defined in the accompanying claims and some of the features may be employed without others.

What I claim as new and desire to secure by Letters Patent is:—

1. In a typewriting machine, the combination of a carriage, a combined paper table and apron, paper feed rollers mounted on the carriage beneath the paper apron, and hand releasable means that enable said combined paper table and apron to be readily removed and give complete access to the feed rollers and their mountings after the platen has been first removed.

2. In a typewriting machine, the combination of a plurality of pairs of sheet metal feed roller hangers pivoted at the lower ends thereof on the carriage and spaced apart above their pivots, the hangers of each pair being disposed one opposite and in front of the other, a set of front paper feed rollers carried by the front hangers, a set of rear paper feed rollers carried by the rear hangers, a hand controlled rock shaft angular in cross section located in the space between the hangers of each pair and above the pivots thereof and cooperative with said hangers to shift them in order to release the feed rollers from the platen, an open-mouth bearing for one end of said shaft, and a hand releasable holding member that may be shifted from a position where it prevents the shaft from moving out of said bearing to a position where the shaft is free to be removed from said bearing and detached from the machine.

3. In a typewriting machine, the combination of a platen, a combined paper table and apron which extends beneath the platen and terminates at its front edge in front of the platen, supporting members beneath the platen on which said combined paper table and apron is pivotally mounted so that the front edge of the paper apron may be pressed against the platen and rocked away therefrom, and means that enable said supporting members to be moved by hand relatively one to the other in order to permit the combined paper table and apron to be detached from said supporting members and removed from the machine.

4. In a typewriting machine, the combination of a carriage, paper feed rollers, releasing means therefor comprising a hand controlled rock shaft, and means for demountably supporting said rock shaft on the carriage comprising an open-mouth bearing on the carriage in which the rock shaft may be seated and rocked, and a hand releasable holding member mounted on the carriage for shifting movement from a position where it prevents the shaft from moving out of said bearing to a position where the shaft is free to be removed from said bearing and detached from the machine.
5. In a typewriting machine, the combination of a carriage, a combined paper table and apron, paper feed rollers mounted on the carriage beneath the paper apron, and hand releasable means that enable said combined paper table and apron to be readily removed and give complete access to the feed rollers and their mountings after the platen has been first removed, said hand releasable means comprising supporting members by which the combined paper table and apron is mounted on the carriage and one of which members is movable relatively to the other to release the combined paper table and apron and enable it to be detached from the carriage.
6. In a typewriting machine, the combination of a plurality of pairs of sheet metal feed roller hangers pivoted at the lower ends thereof on the carriage and spaced apart above their pivots, the hangers of each pair being disposed one opposite and in front of the other, a set of front paper feed rollers carried by the front hangers, a set of rear paper feed rollers carried by the rear hangers, a rock shaft angular in cross section located in the space between the hangers of each pair and above the pivots thereof and cooperative with the flat faces of said sheet metal hangers to shift them in order to release the feed rollers from the platen, a hand controlled crank arm on said rock shaft, and a stop for arresting the motion of said crank arm when oppositely disposed corners of said angular rock shaft are substantially dead centered against the axis of the shaft and under the pressure of the hangers thereon, whereby the feed rollers may be locked or retained in released position under the dead centering force.
7. In a typewriting machine, the combination of a carriage, a paper apron, and means for detachably mounting and pivotally supporting said paper apron on the carriage, said means comprising two supporting brackets on the carriage, one of said brackets being mounted for shifting movement into and out of effective position, the shiftable bracket when in the effective position retaining the paper apron pivoted on the carriage and when in the ineffective position disconnecting said pivotal connection, thereby enabling the paper apron to be detached from the carriage.
8. In a typewriting machine, the combination of a carriage, a paper apron, and means for detachably mounting and pivotally supporting said paper apron on the carriage, said means comprising two supporting brackets on the carriage, one of said brackets being mounted for shifting movement into and out of effective position, the shiftable bracket when in the effective position retaining the paper apron pivoted on the carriage and when in the ineffective position disconnecting said pivotal connection, thereby enabling the paper apron to be detached from the carriage, and means for retaining said shiftable bracket against accidental displacement from either of said positions to which it may be set.
9. In a typewriting machine, the combination of a plurality of pairs of feed roller hangers pivoted at their lower ends on the carriage and spaced apart above their pivots, the hangers of each pair comprising a front and a rear hanger, a set of front paper feed rollers carried by the front hangers, a set of rear paper feed rollers carried by the rear hangers, a hand controlled rock shaft located in the space between the hangers of each pair and above the pivots thereof and cooperative with said hangers to shift them in order to release the feed rollers from the platen, an open-mouth bearing for one end portion of said shaft, and a bracket shiftably mounted on the carriage into and out of effective position and having a latching member that overlies said shaft and prevents it from moving up out of said open-mouth bearing when the bracket is in effective position and releases the shaft and enables it to be moved up out of said bearing and to be detached from the machine when the bracket is in the ineffective position.
10. In a typewriting machine, the combination of a carriage; a paper apron; means for detachably mounting and pivotally supporting said paper apron on the carriage, said means comprising two supporting brackets on the carriage, one of said brackets being mounted for rectilinear and pivotal shifting movement into and out of effective position, the shiftable bracket when in the effective position at one end of its rectilinear movement retaining the paper apron pivoted on the carriage and when in the ineffective position at the other end of said rectilinear movement disconnecting said pivotal connection, thereby enabling the paper apron to be detached from the carriage; paper feed rollers; a releasing rock shaft therefor; and means for detachably mounting said rock shaft on the carriage comprising an open-mouth bearing in which one end portion of said rock shaft is mounted to turn

but from which the shaft may be removed and a latching member carried by said shiftable bracket and overlying said shaft when the shiftable bracket is at one end of its pivotal movement to prevent the shaft from moving out of its open-mouth bearing and carried away from the shaft by a pivotal movement of the bracket in the opposite direction to enable the shaft to be removed from said bearing and detached from the carriage.

11. In a typewriting machine, the combination of a carriage, a paper apron, feed rollers, a releasing device therefor, and means for detachably mounting said paper apron and releasing device on the carriage comprising a holding member shiftable in one direction to release the paper apron for detachment from the carriage and shiftable in another direction to release said feed roller releasing device for detachment from the carriage.

12. In a typewriting machine, the combination of a carriage, forward and rear paper feed roller hangers pivoted at their lower ends and spaced apart above their pivots, paper feed rollers carried by said hangers,

a feed roller releasing rock-shaft located in the intervening space between said forward and rear hangers and above the pivots thereof, said rock shaft being angular in cross section where it coacts with said hangers and having cylindrical bearing portions, supporting brackets having bearings in which the cylindrical portions of the shaft are received and against the sides of which brackets the angular portions of the shaft bear to prevent longitudinal displacement of the shaft in its bearings, one of said bearings being an open-mouth bearing from which one end portion of the shaft may be displaced, and a retaining device shiftable from a position overlying said shaft and where it holds the shaft in its open-mouth bearing to a releasing position where the shaft is free to be displaced from said open-mouth bearing and to be detached from the carriage.

Signed at the borough of Manhattan, city of New York, in the county of New York and State of New York this 16th day of June, A. D. 1926.

EDWIN E. BARNEY.
